UNITED STATES PATENT OFFICE.

FRANK BLANDO, OF NEW YORK, N. Y.

INTERCHANGEABLE FURNITURE.

1,209,664.

Specification of Letters Patent. Patented Dec. 26, 1916.

Application filed February 28, 1916. Serial No. 80,932.

To all whom it may concern:

Be it known that I, FRANK BLANDO, a subject of the King of Italy, residing at New York, in the county and State of New York, have invented certain new and useful Improvements in Interchangeable Furniture, of which the following is a full, clear, and exact specification.

This invention relates to folding sofa beds, 10 that is, furniture which may be converted at will into either a sofa or a bed.

One object of the invention is to produce a device of this kind which may easily be converted from one position to the other by 15 a single operator and by a single operation.

Another object is to simplify the construction of the bed portion, and especially the bed-spring frame, whereby the latter may be folded compactly into the space below and 20 behind the usual upholstery of the sofa.

A further object is to provide a folding structure of this kind in which the bed portions are completely concealed when the device is used as a sofa, and in which the characteristic parts of the sofa are entirely concealed when the device is made up as a bed. To these ends, the parts constituting the bed are adapted to be entirely folded within the customary dimensions of the sofa, without 25 dispensing with the usual upholstery and seat spring, and the characteristic parts of the sofa are arranged entirely below the bed when the device is arranged in the latter form. To make the resemblance to an ordinary bed more complete, head and foot pieces of the usual form are provided, and in order to render the bed structure more rigid, these head and foot pieces are made as single units which are themselves non-foldable but which 30 may be folded as units into the back member 40 of the sofa structure.

The invention will be first hereinafter described in connection with the accompanying drawings which constitute a part of this 45 specification, and then more specifically defined in the claims at the end of this description.

In the accompanying drawings, wherein similar reference characters are used to designate corresponding parts throughout the 50 several views: Figure 1 is a perspective view of the device as it appears when folded into the form of a sofa. Fig. 2 is a rear elevation of the device in this position. Fig. 55 3 is a central vertical section taken from

front to back through the device as illustrated in Figs. 1 and 2. Fig. 4 is a broken perspective view of the device arranged as a sofa, showing the preliminary step of opening the hinged section of the back of the sofa preliminary to converting the device into the form of a bed. Fig. 5 is a longitudinal vertical section through the device showing an intermediate stage in its conversion from a sofa into a bed. Fig. 6 is a longitudinal vertical section through the device arranged as a bed. Fig. 7 is a perspective view of the device arranged as a bed, showing the duplication of levers and links on opposite sides of the bed-spring frame. Fig. 70 8 is a fragmentary detailed view of one form of bed-spring which may be carried by the bed-spring frame. Fig. 9 is a detailed view of the locking device for securing the hinged section of the back of the sofa to the back 75 member of the device, the hook-shaped locking device for securing the head piece in folded position, and the means carried by the hinged section for automatically actuating said hook-shaped locking device when 80 said section is closed. Fig. 10 is a detailed view of one of the spring-pressed latches and keepers for supporting the hinged section away from the floor when the top member of the device is in inverted position, as when 85 arranged as a bed, the spring for automatically opening said hinged section when unlatched from the back member being also illustrated. Fig. 11 is a detailed view of 90 one of the pairs of locking lugs for securing the top member to the back member when the device is arranged as a sofa. Fig. 12 is a cross section through one of the pairs of guides for the free ends of the folding 95 supporting frame for the middle portion of the bed-spring frame, showing the roller bearing and guiding means on said folding supporting frame, and Fig. 13 is a detailed broken side view of this pair of guides and the engaging portion of the folding supporting frame.

The device comprises a base member 1, a top member 2, and a back member 3.

The base member 1 is in the form of a box open at the back but closed at the front and sides and finished like the lower portion of an ordinary sofa. This base member is supported upon casters 4, and may remain stationary during the conversion of the device from one form into the other.

- The top member 2 is hinged at 5 to the front edge portion of the base member, and carries the usual spring upholstered seat 6, arms 7 and a front covering 8 for the back member. Said covering 8 includes a hinged upper section 9 adapted to fit the back member in such a manner as to conceal the fact that it is a separate part when the device is arranged as a sofa.
- 10 The back member comprises an open box-like frame hinged at 10 to the rear edge portion of the base member, see Fig. 3. The lower ends of the side portions of the back member are cut away at an angle to 15 the upper edges of the sides of the base member, as shown at 11 to permit said back member to swing rearwardly to the inclined position shown in Figs. 6 and 7. The space between these cut away edges is covered by 20 a portion 12 of the upholstery material, see Figs. 1 and 5, so that this space is not discernible when the device is arranged as a sofa.
- 25 The top member 2 has a foot piece 13 rigidly secured by straps 14 to its rear face. This foot piece is preferably made as a unit and like that of an ordinary bed. It is secured to the rear face of the top member 2 in inverted position, so that when said top 30 member is swung forwardly through an arc of 180 degrees from the position shown in Figs. 1, 3 and 4, through the intermediate stage shown in Fig. 5, to the position illustrated in Figs. 6 and 7, said foot piece will 35 be in proper relative position to the bed-spring frame. The foot piece carries casters 15 which serve to support the top member 2 in its unfolded position and also helps to make the device resemble an ordinary bed.
- 40 The back member 3 has a head piece 16 connected thereto by pivoted links 17 which permit said head piece to be folded within said back member when the device is arranged as a sofa, and to be extended to the 45 position shown in Figs. 6 and 7 when the device is arranged as a bed. The upper pair of links 17 also constitute supports for the top portion 18 of the back member when the latter is swung rearwardly to the position 50 illustrated in Figs. 6 and 7. The head piece is also provided with casters 19 having a corresponding function to those on the foot piece.
- 55 The bed-spring 20 is made in sections 21, 22, 23, 24 and 25 pivotally connected to one another at 26, 27, 28 and 29. The end section 21 of said bed-spring frame nearest the foot piece is pivotally connected to the bottom of the top member 2 by links 30. This 60 end section does not extend the full width of the top member, that is, from front to back of the upholstered seat 6, the pivotal connection 26 between it and the next section 22 of the bed-spring frame being within 65 the borders of said seat portion 6 of the top

member 2. The section 22 of the bed-spring frame is supported away from the seat portion 6 of the member 2 by straps 31 rigidly secured to the seat portion and pivotally connected to the section 22 between the 70 pivotal connections 26 and 27, Figs. 6 and 7. Pivotal links 32 extend between the front edge portion of the base member 1 and the pivotal points 27 at the juncture of the bed-spring sections 22 and 23. These links 32 in 75 conjunction with the straps 31 and links 30 serve to support the sections 21 and 22 of the bed-spring frame in horizontal position when the device is arranged as a bed, and permit said sections to be automatically folded through the steps illustrated in Figs. 5 and 3 when the device is converted into a sofa.

80 The connected ends of the sections 23, 24 and 25 of the bed-spring frame are supported by means of a folding frame 33, Figs. 6 and 7, when the device is arranged as a bed. This folding frame 33 is pivoted to the sections 23 and 24 at the point of pivotal connection between them, and the 85 lower free end of said frame is arranged between pairs of guide strips 34 and 34^a in the base member. As best shown in Figs. 12 and 13, the lower free end of the folding frame 33 may have laterally projecting pins 90 or lugs 35 extending between corresponding pairs of the guide rods 34. These guide rods cause the lower ends of the folding frame to travel in a substantially horizontal plane as the device is folded up, thereby drawing 95 the middle portions of the bed-spring frame down into the base member through the steps illustrated in Figs. 5 and 3. The lower guide strip 34 is arranged out of vertical alignment with the upper strip 34^a as shown 100 in Fig. 13, and the folding frame 33 is provided with roller bearings 35^a at its lower edge to rest upon the lower guide strip 34 and insure free movement of the free end of the folding frame along the guides. The 105 lugs 35 may consist of extensions of the axles of the rollers, as shown in Fig. 13. Said folding section 33 is automatically operated by means of links 36 spaced below and arranged parallel to the section 23 of 110 bed-spring frame, links 37 arranged parallel to the folding frame 33, and links 38 pivotally connecting the front edge portion of the base member with the adjacent ends of the links 36 and 37. As clearly illustrated in Figs. 115 6 and 7, the links 36 are connected at their opposite ends to the folding frame 33 and the links 38, while the links 37 are dropped from the section 23 of the bed-spring frame to the points of pivotal connection between 120 the links 36 and 38. The links 36 and 37 in conjunction with the upper portion of the folding frame 33 and the section 23 of the bed-spring frame form parallelograms and 125 thus make it possible for the frame 33 to 130 135

be folded or extended automatically as the top member 2 and back member 3 of the device are moved from one position to the other.

- 5 The outer end of the section 25 of the bed-spring frame, which is arranged adjacent the head piece 16, has sliding connection with rods 39 rigidly secured at their upper ends to the top piece 18 of the back member
- 10 3. These rods 39 are flexible to a limited extent and are curved downwardly, having their lower free ends 40 connected to a cross piece 41 of the base member by chains 42 or other suitable flexible connections. As illustrated, the end section 25 of the bed-spring frame has perforated lugs 39a through which the rods 39 extend and by means of which the sliding connection between said rods and end section is made. As the device is converted from a sofa into a bed, the free end of the section 25 slides along the rods 39 from the position illustrated in Fig. 3 to the position shown in Figs. 6 and 7, and when in the latter position, is arranged near the upper ends of said rods where there is practically no flexibility, so that in this position the end of the section 25 is rigidly supported by said rods.

The automatic folding and unfolding of the back member 3 during the swinging of the top member 2 from one of its positions to the other is accomplished through the instrumentality of lever arms 43 rigidly connected to the back member and having their forward ends connected by pairs of links 44 and 45 to the pivotal connections 27 between the sections 22 and 23 of the bed-spring frame. As illustrated in Figs. 3, 5, 6 and 7, the links 44 are connected directly to the lever arms 43, while the links 45 connect the links 44 to the pivotal connections 27 between the bed-spring sections 22 and 23. The lever arms 43 have stop lugs 46 arranged in the path of the links 44 in order to limit the rotation of said links 44 at the proper point to act positively on said lever arms for raising the back member 3 as the bed-spring frame is folded. The position of the links 44 in contact with the stop lugs 46 is illustrated in Fig. 5, where the back member is partially raised. When the back member has been fully raised and the device completely folded into the form of a sofa, the links 44 and 45 are extended as illustrated in Fig. 3, while in the unfolded position of the device, that is, when arranged as a bed, said links are folded upon one another, as shown in Figs. 6 and 7. In folded position, the top member 2 is locked to the back member 3 by rigid hook-shaped catches 47 projecting from the rear face of the top member and adapted to engage over laterally projecting lugs 48 on the inside of the back member, Figs. 3 and 11. The catches 47 are preferably arranged on the top mem-

ber adjacent the hinges 49 of the section 9. These hinges 49 are provided with springs 50, Fig. 10, which automatically open the section 9 when it is unlatched from the back member 3.

When the device is arranged as a sofa, the section 9 is locked in closed position by a hook-shaped catch 51 on said section engaging a spring-pressed keeper 52 carried by the top piece 18 of the back member. The keeper 52 is provided with a push button 53 projecting from the top piece 18, the spring 54 which normally holds the keeper in position to be engaged by the catch 51 being interposed between said push button 53 and the base of the socket in which said push button is arranged. By reason of this construction, the hook-shaped catch 51, which has a beveled end 55 for that purpose, will be automatically engaged with the keeper 52 when the section 9 is closed. Pressure upon the push button 53 will release said catch 51, and when released, the springs 50 in the hinges 49 will automatically open the section 9, throwing it forward upon the arms 7 as shown in Fig. 4. The top piece 18 of the back member 3 also carries a hook-shaped locking device 56 for securing the head piece 16 in folded position as shown in Fig. 3, said catches engaging the horizontal bar of the head piece. This locking device 56 is connected to the strip 18 by a spring hinge 57, Fig. 9, which normally holds said device in unlocked position so as to permit the head piece 16 to be extended. The hinged section 9 carries blocks 58 on its inner face, and when said section is closed and locked to the strip 18 by the catch 51 and keeper 52, the blocks 58 engage the locking device 56 and move it from the unlocked position shown in Fig. 9 to the locked position shown in Fig. 3. As soon as the section 9 is released from the strip 18 and is thrown forward upon the arm 7 by the springs 50 in the hinges 49, the locking device 56 will be moved to unlocked position by the spring in its hinge 57, thus releasing the head piece 16.

In order to support the hinged section 9 away from the floor when the top member 2 is inverted as shown in Figs. 6 and 7, the hinged edge of said section is provided with projecting lugs 59 extending into engagement with spring-pressed bolts 60 on the rear face of the top member just below the section 9. These bolts 60, of which there are two, one being arranged at each side of the device and extending in opposite directions, may be withdrawn for releasing the lugs 59 by means of a wire 61 connecting the two bolts and having a finger ring 62 arranged about midway between them.

The bed-spring frame 20 may be equipped with any suitable form of bed-spring capable of folding with the sections of said

frame. The preferred form of spring is that generally known as the National spring illustrated at 63 in Fig. 8.

When it is desired to convert the device 5 from the form of a sofa illustrated in Figs. 1 and 3 into the form of a bed, the operator first presses upon the push button 53 which protrudes slightly but inconspicuously from the top piece or strip 18 of the back member 3, thereby releasing the catch 51 from the keeper 52, whereupon the hinged section 9 will be thrown forward upon the arm 7 by the springs 50 in the hinges 49. This is the first step in the unfolding operation and is 10 shown in Fig. 4. As already explained, the opening of the section 9 releases the locking device 56 from the head piece 16. The operator then grasps a portion of the top member 2, or preferably the cross piece 64 of the 15 foot piece 13 which is arranged within the back member just behind the top member, and by pulling upwardly swings the top member forwardly upon the pivots 5 through the intermediate stage shown in Fig. 5 to 20 the fully inverted position illustrated in Figs. 6 and 7. During this opening movement of the top member 2, the bed-spring frame 20 is straightened out, the sections 21 and 22 thereof being raised upon the bottom 25 of the member 2, the sections 23 and 24 being raised by means of the links 32, 36, 37 and 38 and the supporting frame 33, and the section 25 being also straightened out by having its perforated lugs 39 moved along 30 the rods 39 while the back member 3 is swung rearwardly by the lever arms 43 actuated by the links 44 and 45 connecting said lever arms with the pivotal connections 27 between the sections 22 and 23 of the bed-spring 35 frame. As the back member 3 is swung rearwardly, the head piece 16 is moved out by the links 17 to the vertical position shown in Figs. 6 and 7, and when said back member is swung fully backward, its top piece or 40 strip 18 will rest upon the upper links 17 and firmly support the head end of the bed-spring frame in proper position. It will be noted that this entire operation is accomplished by simply swinging the top section 45 2 outwardly through an arc of 180 degrees, which may be easily accomplished by a single operator.

For folding the device from the form of a bed into a sofa the operations just described 55 are simply reversed. The operator grasps the foot piece 13 and swings the top member 2 upwardly and rearwardly from the position shown in Figs. 6 and 7 through the intermediate stage shown in Fig. 5, to the position illustrated in Fig. 4. During this movement, the links 32, 36, 37 and 38 automatically fold the supporting frame 33 and lower the middle sections of the bed-spring frame, while the sections 21 and 22 of said bed- 60 65 spring frame are folded with the top mem-

ber 2, and the section 25 is folded into vertical position by reason of its sliding connection with the rods 39. The links 44 and 45, by reason of the stop lugs 46, act upon the lever arms 43 to raise the back member 3 into 70 closed position as the bed-spring frame is folded and the top member 2 turned over into position for forming the sofa. It may here be noted that the pivotal connections 29 between the sections 24 and 25 of the bed-spring frame are supported in the horizontal plane of the other sections of said frame by links 65 and 66, the latter being a very short link connecting the link 65 with the link 36 as shown in Figs. 6 and 7. As the 75 back member 3 is swung upwardly and forwardly, the links 17 fold the head piece 16 into said back member, so that the top cross bar of said head piece is in position to be gripped by the locking device 56 when the 80 section 9 is closed and locked by the catch 51 and keeper 52. When the top member 2 is returned to the position shown in Figs. 1, 3 and 4, the catches 47 engage with the lugs 48 to lock said top member to the back member against accidental separation one from the other. It will be noted that as the top member 2 swings on the pivots 5, the hooked ends of the catches 47 will move in an arc which will carry them over the lugs 48 when 85 the back member is fully raised, and that when the top member is swung upwardly and forwardly to open the device, the catches 47 will be raised out of engagement with the lugs 48.

Having thus described my invention, what I claim as new and desire to secure by Letters Patent of the United States is:

1. In a folding sofa bed, the combination, with a base member, of a top member hinged to the front edge of the base member and adapted to swing through an arc of substantially 180 degrees to form a front extension for the bed, a back member hinged to the rear edge portion of the base member and adapted to swing rearwardly to an inclined position when the device is arranged as a bed, a continuous bed-spring frame made in sections which are made independent of the base, top and back members but carried thereby, means for supporting the top and back members in position to support the bed-spring frame, and means for automatically folding the bed-spring frame, the supports and the back member when the top member is folded into position to form a sofa.

2. In a folding sofa bed, the combination, with a base member, of a top member constituting the upholstered portion of the sofa and hinged to the front edge portion of the base member, a back member hinged to the rear edge portion of the base member, a continuous bed-spring frame made in sections independent of but carried by the base, top 125 130

- and back members, and adapted to be folded with said members when brought into position to form a sofa, supports for the top and back members when in position to form a bed, and means for automatically unfolding the bed-spring frame or extending it into horizontal position as the top member is swung forwardly through an arc of substantially 180 degrees.
- 10 3. In a folding sofa bed, the combination, with a base member, of a top member hinged to the front edge portion of the base member, a foot piece similar to that of an ordinary bed carried by the top member, a back member hinged to the rear edge portion of the base member, a head piece similar to that of an ordinary bed carried by the back member, a continuous bed-spring frame made in sections independent of but carried by the base, top and back members and adapted to be folded with said members into position to form a sofa, and means for automatically folding the bed-spring frame, the back member and the head and foot pieces when the top member is folded into position to form a sofa.
- 15 4. In a folding sofa bed, the combination, with a base member, of a top member hinged to the front edge portion of the base member, a back member hinged to the rear edge portion of the base member, supports for the top and back members when in position to form a bed, a continuous bed-spring frame made in sections independent of but carried by the base, top and back members and adapted to be folded with them when brought into position to form a sofa, and means for automatically unfolding the bed-spring frame or extending it into horizontal position when the top section is swung forwardly to an inverted position.
- 20 5. In a folding sofa bed, the combination, with a base member, of a top member hinged to the front edge portion of the base member, a back member hinged to the rear edge portion of the base member, supports for the top and back members when in position to form a bed, a continuous bed-spring frame made in sections independent of but carried by the base, top and back members and adapted to be folded with said sections when brought into position to form a sofa, the connecting means between the end portions of the bed-spring frame and the top member and back member, respectively, also serving to support said end portions of the bed-spring frame in horizontal position when the device is arranged as a bed, a folding supporting frame for the middle portion of the bed-spring frame resting upon the base member, means for automatically folding said supporting frame as the device is converted from a bed into a sofa, and means for automatically unfolding the bed-spring frame and extending it into horizontal posi-
- 25 6. In a folding sofa bed, the combination, with a base member, of a top member hinged to the front edge portion of the base member, a back member hinged to the rear edge portion of the base member, a foot piece similar to that of an ordinary bed rigidly secured in inverted position to the rear face of the top member, a head piece similar to that of an ordinary bed pivoted to the back member and adapted to be automatically folded within said back member as the device is converted from a bed to a sofa, a sectional bed-spring frame having portions connected to the base, top and back members and adapted to be folded with said members when brought into position to form a sofa, the foot piece being arranged immediately in front of the head piece and in inverted position when the device is thus folded, and means for automatically unfolding the bed-spring frame or extending it into horizontal position as the device is converted from a sofa into a bed.
- 30 7. In a folding sofa bed, the combination, with a base member, of a top member hinged to the front edge portion of the base member, a back member hinged to the rear portion of the base member, supports for the top and back members when the device is arranged as a bed, a continuous sectional bed-spring frame having portions connected to the base and top sections, downwardly inclined rods carried by the back member and having sliding connection with the head end of the bed-spring frame for automatically folding or extending that end portion of the bed-spring frame as the device is converted from one form into the other, said rods having their upper ends rigidly connected to the back member, flexible connections between the lower ends of said rods and the rear portion of the base member, and means for automatically folding or unfolding the other portions of the bed-spring frame as the device is converted from one form into the other.
- 35 8. In a folding sofa bed, the combination, with a base member, of a top member hinged to the front edge portion of the base member, a back member hinged to the rear edge portion of the base member, a continuous sectional bed-spring frame, one end portion thereof having sliding connection with the back member for automatically folding or extending the same as the device is converted from one form into the other, the other end portion of the bed-spring frame being connected to the top member by pivoted links, and the middle portion of said bed-spring frame being connected to the base member by folding links and supports, whereby said middle portion of the bed-spring frame will be automatically lowered

or raised as the end portions thereof are folded or unfolded in converting the device from one form into the other.

9. In a folding sofa bed, the combination, 6 with a base member, of a top member hinged to the front edge portion of the base member, a back member hinged to the rear edge portion of the base member, a bed-spring frame, one end portion of which has sliding 10 connection with the back member, the other end portion of said frame being connected to the bottom of the top member, the middle portion of said frame being connected to the base member by folding supports, 15 and means for lowering the middle portion of said frame, folding the foot end portion thereof over said middle portion and the head end portion into substantially vertical position when the device is converted 20 from a bed into a sofa.

10. In a folding sofa bed, the combination, with a base member, of top and back members hinged thereto, a bed-spring frame carried by said members and adapted to be 25 folded or unfolded as the device is converted from one form into the other, means for locking the back member to the top member when the device is arranged as a sofa, a section hinged to the top member and constituting 30 a portion of the back of the sofa, and means for locking said section to the back member when the device is arranged as a sofa.

11. In a folding sofa bed, the combination, 35 with a base member, of top and back members hinged thereto, a bed-spring frame carried by said members and adapted to be folded or unfolded as the device is converted from one form into the other, means 40 for locking the back member to the top member when the device is arranged as a sofa, a section hinged to the top member and constituting a portion of the back of the sofa, means for locking said section to the 45 back member when the device is arranged as a sofa, and means for holding said section in open position and away from the floor when the top member is in position to form a bed.

12. In a folding sofa bed, the combination, 50 with a base member, of top and back members hinged thereto, a bed-spring frame carried by said members and adapted to be folded or unfolded as the device is converted 55 from one form into the other, means for locking the back member to the top member when the device is arranged as a sofa, a section hinged to the top member and constituting a portion of the back of the sofa, 60 means for locking said section to the back member when the device is arranged as a sofa, spring latches for holding said section in open position and away from the floor when the top member is in position to form 65 a bed, and means for releasing said latches,

said means being accessible within the back member when the device is folded into the form of a sofa.

13. In a folding sofa bed, the combination, 70 with a base member, top and back members hinged to the base member, a bed-spring frame carried by said members and adapted to be folded or unfolded as the device is converted from one form into the other, a head piece similar to that of an ordinary bed 75 carried by the back member and adapted to fold within the same when the device is in the form of a sofa, a section hinged to the top member and constituting a portion of the back of the sofa, means for locking said 80 section to the back member, and locking means for securing the head piece in the back member, said locking means being automatically operated by the opening or closing of said section. 85

14. In a folding sofa bed, the combination, 90 with a base member, of top and back members hinged to said base member, a sectional bed-spring frame having portions connected to the base, top and back members, a supporting frame pivoted to one portion of the bed-spring frame, guides on the base member for the free ends of said supporting frame, and means for automatically folding 95 said supporting frame as the device is converted from a bed into a sofa. 95

15. In a folding sofa bed, the combination, with a base member, of top and back members hinged to said base member, a sectional bed-spring frame having portions 100 connected to the base, top and back members, a supporting frame pivoted to one portion of the bed-spring frame, and means for automatically folding said supporting frame as the device is converted from a bed into a 105 sofa.

16. In a folding sofa bed, the combination, 110 with a base member, of top and back members hinged to the base member, a hinged section constituting a portion of the top member and a closure for the front of the back member, a head piece similar to that of an ordinary bed connected to the back member and adapted to fold into the same when the device is arranged as a sofa, a 115 hook-shaped locking device carried by the back member and adapted to engage the head piece for retaining the latter in folded position, resilient means for normally holding said locking device in position for releasing the head piece, and means on the hinged section of the top member for automatically moving the locking device into engagement with the head piece when said section is closed. 120

17. In a folding sofa bed, the combination, 125 with a base member, of top and back members hinged to the base member, a hinged section constituting a portion of the top member and a closure for the front of the back 130

member, a head piece similar to that of an ordinary bed connected to the back member and adapted to fold into the same when the device is arranged as a sofa, a hook shaped locking device carried by the back member and adapted to engage the head piece for retaining the latter in folded position, and means

on the hinged section of the top member for automatically moving the locking device into engagement with the head piece when 10 said section is closed.

In testimony whereof I have signed my name to this specification.

FRANK BLANDO.
